(57) **CLAIM**

The ornamental design for a jewelry element, as shown and described.

DESCRIPTION

FIG. 1 is a front elevational view showing my new design:

FIG. 2 is a right side elevational view thereof;

FIG. 3 is a top plan view thereof;

FIG. 4 is a left side elevational view thereof;

FIG. 5 is a rear elevational view thereof; and,

FIG. 6 is a bottom plan view thereof.

The broken lines along the outer top surface and the inner top surface of the jewelry element define the boundaries of the claim and form no part of the claimed design.
